UNITED STATES PATENT OFFICE.

OSCAR J. OLSON, OF DULUTH, MINNESOTA; CARRIE OLSON ADMINISTRATRIX OF SAID OSCAR J. OLSON, DECEASED.

POWER-SHOVEL.

No. 826,051.

Specification of Letters Patent.

Patented July 17, 1906.

Application filed March 31, 1905. Serial No. 253,030.

To all whom it may concern:

Be it known that I, OSCAR J. OLSON, a citizen of the United States, residing at Duluth, in the county of St. Louis and State of Minnesota, have invented certain new and useful Improvements in Power-Shovels; and I do hereby declare the following to be a full, clear, and exact description of the invention, such as will enable others skilled in the art to 10 which it appertains to make and use the same.

My invention relates to power-shovels, and has for its object the production of a simple and convenient power-shovel apparatus 15 adapted for ditch-digging or for various other purposes.

It consists, in combination with a suitable support, of a derrick mounted thereon, a shovel-pole loosely secured to said derrick 20 and provided at its foot with a shovel, means for operating said derrick, and means for operating said shovel.

It also consists of certain other constructions, combinations, and arrangements of 25 parts, as will be hereinafter described and claimed.

In the accompanying drawings, Figure 1 represents a perspective view of my said invention, partly broken away. Fig. 2 is a 30 side elevation, partly in section and partly broken away, of a modified form of my said invention.

In said drawings, 1 is a railway-track laid in short sections adapted to be alternately 35 taken up and removed to the rear as the shovel-supporting car retreats. Supported upon said track is a car 2, upon which is mounted a derrick-base 3, slotted, as at 3^a, to form a cable-passage. Upon said base is an 40 apertured base-plate 4, upon which is erected a horizontally-oscillating derrick-mast 5, in which is formed in any suitable manner a passage 5^a, connecting with the aperture in said plate. The foot of said mast is secured 45 in position against horizontal movement in any suitable manner, as by forming a reduced end (not shown) thereon, adapted to project into the aperture on said plate. The upper end of the mast is secured in position 50 by any suitable guys or braces, as by the braces or guys 6, 7, 8, and 9, which in the construction illustrated are provided at their upper ends with apertured straps, as 10, adapted to loosely engage a pin 11, extend-

ing from the upper end of said mast, thus 55 keeping the mast in a vertical position, but permitting it to oscillate horizontally. Said braces or guys 6 and 7 in the construction illustrated extend oppositely from said mast and at their lower ends are braced from said 60 car by any suitable braces, as 6^a and 7^a, respectively. At the junction of said guys with said braces are preferably mounted thereon in any suitable manner boxes or cribs X, (shown in broken lines in Fig. 1,) adapted 65 to receive stone or other weights, in which case said guys, braces, and boxes when the machine is in operation will preferably be further supported in any suitable manner by underlying blocks (not shown) laid upon the 70 ground, or instead or in addition said guys and braces may be supported from the ground by jack-screws Y, of any suitable construction, at the sides of the track. The lower ends of the braces or guys 8 and 9 are preferably secured to the frame of the car, near the 75 rear end thereof, in any suitable manner; but since said mast may be braced or guyed in various ways or by various means within the spirit and scope of my invention I do not desire to be limited to the exact means for that 80 purpose which I have illustrated. Pivotedly secured to said mast in any suitable manner, as at 12, is a derrick pole or jib 13, supported at its upper end by a chain or cable 14, secured at 85 one end to either said pole or mast, as preferably at 14^a, and rove through a suitable number of sheaves or pulleys, as 15, some of which are secured to said pole and one or more of which are secured to said mast, the opposite 90 end of said cable being preferably secured to a cleat on said mast, as indicated in broken lines at 14^b, Fig. 1, and in solid lines at 14^b, Fig. 2, by which cable the vertical angle of said derrick-pole may be adjusted; but since 95 said cable may be connected with said pole or mast or with said pole and some other anchorage than said mast in a variety of ways within the spirit and scope of my invention I do not desire to be limited to the specific 100 means or manner shown for such purpose. Secured to said mast, intermediate of the ends thereof and preferably in a rigid manner, as by bolts 16^a, is a guide or spreader 16 of any suitable construction. Cables 17 and 105 18, respectively, are secured in any suitable manner to said derrick-pole, respectively, on opposite sides thereof, as at 17^a, and are

adapted to be engaged by said guide 16 at opposite sides of said mast, and said cables are engaged at their opposite ends by any suitable operating means, as by winding-drums 19 and 19^a, respectively, on a hoisting-engine 20. The operation of said guide 16 is to deflect the course of said cables 17 and 18, thus providing a greater leverage upon said derrick-arm through said cables. A further result is to transmit through said guide a direct swinging strain upon said mast, thus avoiding some of the strain which would otherwise be imposed upon the pivot-pin of said derrick-arm. It is obvious that by slackening one of said cables 17 or 18 and drawing taut the other of them said derrick-arm may be swung to one side or the other, as desired. Upon said derrick-pole is secured a clip 21, to which a collar 22 is pivotally secured by a universal joint of any suitable construction, as 23. A shovel-pole 24 is loosely encircled by said collar and is provided at its lower end with a scoop or shovel 25, preferably directed toward said car. To the forward end of said shovel is secured a crotch-line 26, to which is attached a sheave or pulley 27, through which pulley is rove a cable 28, which is secured at one end to a suitable anchorage, as at 28^a, to said car, and intermediate of said pulley and its opposite end is carried between or partly around suitable guide-wheels, as at 28^b, 28^c, and 28^d, and said opposite end thereof is secured to a winding-drum or windlass of any suitable construction, as to the drum 29, which may be operated by any suitable means, as by said engine 20. The engine 20 and said winding-drums are of well-known construction and in common use and are not thought necessary to be herein described; nor do I desire to limit myself to any specific kind of cable-operating means, since said cables might be operated by any one or more of a great variety of means. Secured to said shovel is another cable 30, which is carried over a guide-pulley 30^a on the upper end of said derrick-pole and thence over a guide-pulley 30^b on said mast and thence under a guide-pulley 30^c and secured at its opposite end to a windlass of any suitable structure, as 31, operated by any suitable means, as by said engine. It will be obvious that by slackening both said cables 28 and 30 said shovel will drop by gravity, said shovel-pole slipping through the collar 22. Now by winding up the cable 28, leaving the cable 30 slack, the shovel will be drawn toward the car along the bottom of the ditch or against the bank upon which the car stands, thus securing a load of earth or ore. As soon as the shovel is filled both cables 28 and 30 are wound up, which operate to lift the shovel, the shovel-pole slipping through said collar 22. After the shovel reaches a certain height—that is to say, the height of the pulleys 28^b—said cable 28 may be slowly un-

wound to permit the shovel to be raised higher, but not to be tipped by the cable 30.

When the shovel has reached the desired height, the derrick pole or jib may be swung to one side or the other by one or the other of the cables 17 or 18 until the shovel is over the dump, whereupon the cable 28 will be rapidly slackened and the cable 30 wound up, thus swinging the shovel vertically in an arc of which said universal joint 23 is the radial center and causing said shovel to discharge its load. If desired, said derrick may be mounted upon a scow or other suitable support, (not shown, but the construction of which would occur to one skilled in the art,) and, if desired, said shovel 25 may, as shown in Fig. 2, be turned around, so as to fill while moving away from the derrick-support, in which latter case the closed end of the scoop or shovel will be provided with an outwardly-opening latched door 25^a, having a latch-releasing cord or wire 32, secured to the latch 33 thereof and carried over any suitable purchase-point or guide-wheel 34, and thence to said car or other support, so that said door may be released and the load of earth dropped through the doorway to the dump. In such case also the cable 30 would draw the scoop in load-receiving direction as well as to dumping position, the cable 28 only operating to draw back the shovel to the starting position and subsequently in coöperation with the cable 30 to lift the load. Such modification will, it is thought, be obvious to any one skilled in the art and need not be illustrated or described more particularly. In said modified form I also prefer to furnish holddown means for holding said shovel-pole in lowered position until the shovel or scoop is filled. Gravity is usually sufficient for this purpose in either form of the device; but such additional means, which I will now describe, I believe is desirable in such modified form, at least, and may also, if desired, within the scope of my invention be added to the construction shown in Fig. 1. Said holddown means comprise a cable or equivalent flexible means 35, secured at one end to the foot of said pole by said scoop or in any other manner and thence led upwardly and partly around a guide-wheel 36, mounted on said collar, and thence to and several times around a drum 37, preferably mounted on said jib, and thence to and partly around a guide-wheel 38, mounted on said collar, and thence upwardly and secured at its opposite end to said pole in any suitable manner, as at 38^a. Said drum may be controlled in any suitable manner; but I prefer to secure a concentric brake-wheel 39 thereto and to bend over said wheel a brake-strap 40, secured at one end, as at 40^a, to said jib and at its opposite end to the toe of a bell-crank lever 41, which is pivoted at its heel to said jib, as at 41^a.

43. To the opposite end of said lever I secure a hauling-line 44, leading toward the car, by which said lever may be rocked to set said brake-strap in operation.

5 Having now described my invention, what I claim, and desire to secure by Letters Patent, is—

1. The combination with a suitable support of a jib, a collar mounted on said jib by a universal joint, a pole directed loosely through said collar, a shovel carried by said pole, means for lowering and raising said pole and means for swinging said pole.

2. The combination with a suitable support of a jib carried thereby, a collar secured to said jib by a universal joint, a pole directed loosely through said collar, guides mounted on said collar, flexible means en-

gaging said guides and secured to said pole and adapted to control the movement of said pole through said collar, means mounted on said jib and engaging said flexible means intermediate of its ends and adapted to govern the movement of said flexible means, a shovel carried by said pole, means for drawing said shovel in digging engagement with the earth, and means for swinging said shovel into load-releasing position, substantially as described.

In testimony whereof I hereunto affix my signature in presence of two witnesses.

OSCAR J. OLSON.
